UNITED STATES PATENT OFFICE.

AUGUST SZARKA, OF BARBERTON, OHIO.

WATER HEATER.

Application filed December 31, 1926. Serial No. 158,176.

This invention relates to water heaters, particularly of the instantaneous type.

The general purpose of the invention is to provide an improved heater capable of more efficient heating while at the same time being easily cleaned and inexpensively repaired.

The foregoing and other objects are obtained by the construction illustrated in the accompanying drawings and briefly described below. It is to be understood that the invention is not limited to the specific form thereof shown and described.

Of the accompanying drawings,

Figure 1 is an elevation of an improved heater embodying the invention;

Figure 2 is a section on line 2—2 of Figure 1;

Figure 3 is a section on line 3—3 of Figure 1; and

Figure 4 is a section on line 4—4 of Figure 1.

Referring to the drawings, the numeral 10 represents a duplex header having a water inlet at 11 and a water outlet at 12. The header 10 is divided by vertical partitions 13, 13 and 14, 14 and vertically spaced horizontal partitions 15 into a series of horizontally extending courses having pairs of offset communicating pockets 16 and 17 arranged in each course. As shown in Figure 3, the inlet 11 empties into a pocket 16 on an end of the lowermost course. Connected with and extending laterally from each pocket 16 of the header 10 is an open end tube 19 of comparatively small bore into which water may flow from pockets 16 and connected onto each pocket 17 is a closed end tube 18 arranged about tubes 19 into which water may flow from tubes 19 and emptying into the pocket 16 of a succeeding pair of pockets.

To deliver water from one course to another higher course, they are connected alternately at opposite ends by ports indicated at 20 and 21, the highest course having outlet pipe 12 connected therewith. The arrangement of the courses of header pockets 16 and 17 is such that alternate pairs of tubes 18 and 19 are offset or staggered both horizontally and vertically.

To the header 10 a suitable casing 23, here

shown of U-shape, may be removably secured as by screws 24, 24. The casing 23 may be lined with a heat-insulating material, such as asbestos 24^a, and may have doors 25, 25 therein. The tubes 18 and 19 are preferably removably secured to the header by being threaded into the walls or partitions thereof to permit easy removal for cleaning and to provide for inexpensive repairing by replacement of leaky tubes.

The bottom of casing 23 is open and a gas burner 26 is set therein so that the gaseous products of combustion from the burner will pass upwardly through the casing about tubes 18. The top of the casing 23 is closed, but provided with an aperture 23^a to which is connected a flue pipe 23^b.

Burner 26 is connected to a fuel supply through a valve 27 to a supply line 28. A by-pass 29 around the valve is connected to a pilot 30 for the burner. Valve 27 is arranged to be controlled by drawing of water from the system through the heater by means of a flap 31 arranged in water supply line 32 and connected to an arm 33 in turn connected by a link 34 to an operating arm 35 from valve 27. A spring 34^a is arranged to close valve 27 when the water is shut off.

In use, the pilot 30 will be permanently lighted. Upon drawing water from a faucet (not shown) on the delivery line 12 the flow of water in pipe 32 will operate flap 31 to swing arm 33 upwardly and through link 34 will open valve 27 to supply gas to burner 26. The water will pass into the header 10 and will flow outwardly from the header in the large tubes, then back to the header in the small tubes following each horizontal course from one end to the other and alternate courses in opposite directions, thus flowing in a zigzag path upwardly to the delivery pipe 12.

It will appear that the cooler water flows first through the outer tubes 18 having direct contact with the burner gases. In addition to effectively heating the water by this provision, these tubes are cooled by the water to prevent rapid deterioration by oxidation thereof. The inner tubes are not subject to oxidation, being protected by the water in 100

tubes 18 from the effect of any heat and air thereon.

Modifications of the invention may be resorted to without departing from the spirit thereof or the scope of the appended claims.

5 What is claimed is:

1. A water heater comprising a series of horizontally and vertically offset pairs of tubes arranged in horizontal courses, one 10 course above the other, each pair of tubes including an outer closed end tube and an inner open ended tube enclosed by the outer tube, a header arranged to deliver water to the inner tubes and to receive the water 15 from the outer tubes in succession and to deliver water from one end of one course to the adjacent end of a higher course in succession so that the water will follow a zig-zag path upwardly, said tubes being removably secured to and supported entirely by the header, a casing surrounding the tubes and removably mounted on the header, and a 20 gas burner at the bottom of the casing for providing heated gases of combustion to pass upwardly about the tubes, said burner being supported on the header.

2. A water heater comprising a series of pairs of tubes arranged in courses, one course above the other, each pair of tubes including 30 an outer closed end tube and an inner open ended tube enclosed by the outer tube, a header arranged to deliver water to the inner tubes and to receive the water from the outer tubes in succession and to deliver water 35 from one end of one course to the adjacent end of a higher course in succession, said tubes being removably secured to and supported entirely by the header, a casing surrounding the tubes and removably mounted on the header, and a gas burner at the bottom 40 of the casing for providing heated gases of combustion to pass upwardly about the tubes, said burner being supported on the header.

45 AUGUST SZARKA.
